2

Arrangements for switching on electric apparatus and for initiating processes are already known. Such devices are employed in particular in connection with telephonographs which must be controlled by telephone calls either for the reproduction of recorded messages or for the reception of communications. It is evident that unauthorized persons must be prevented when calling up from listening in on recorded communications. For this purpose devices have been invented which, after the telephonograph has been set in motion, transmit to the caller at fixed intervals signals such that the caller must in turn emit signals after pauses corresponding to a prearranged key or code. These signals, assumed always that they correspond to the prearranged key, set in motion the reproducing apparatus.

Arrangements of this type can, however, also be utilized for any other purpose, such as for switching on electric apparatus of any kind or for releasing mechanical devices. In this case, too, the preliminary insertion of the abovementioned device, which we may call a secret lock, affords a guarantee that unauthorized persons cannot initiate the process.

The devices for effecting the switching on or initiating of processes by telephone calls dependent on a prearranged key and therefore on prearranged signals given at fixed intervals are, however, of extremely complicated design and construction. Secret locks of this type should also admit of as many variations of the key as possible. This requirement must not, on the other hand, render the installation economically impracticable.

The present invention relates to a secret lock of this kind for arrangements enabling processes to be switched on and initiated by telephone calls. It is characterized by simplicity of construction and a wide range of variation of the key. In the arrangement for initiating processes by means of telephone calls the subscriber's calling circuit as usual actuates a device transmitting at fixed intervals signals (for example a series of numbers) between which the caller can emit order impulses of any desired frequency, which, occurring during the prearranged pauses, cause processes to be switched on and initiated. This device is characterized in that a selector mechanism with several switch buttons, to each of which corresponds a contact controlled by a cam, is connected with a first relay, while a second relay can be actuated by the order impulses. Both of these relays are connected with a third, multi-coil block-relay corresponding to a switching device in such a way that this third relay is not excited only when both the other relays are simultaneously excited or simultaneously not excited. The result is that when no order

impulse is received or one is received at the wrong moment the switch device is blocked.

It has been found convenient to design the arrangement so that the circuit of each switch button of the selector mechanism is closed by pressing the corresponding button. This closes the cam-controlled contact and consequently excites the relay connected with the selector mechanism. Another practical measure is to shift the cams controlling the contacts of the switch buttons in such a way that the contacts of the single buttons are actuated successively at intervals. A suitable embodiment of the selector mechanism has 10 buttons, giving 1024, viz. 2¹⁰ different keys. The great variety of keys, together with the fact that the key can be easily altered at any time, ensures the greatest possible security against interference by unauthorized persons.

Besides the above-mentioned block-relay the circuit of the switching device also contains a cam-controlled contact. This can only be closed when all the cam-controlled contacts of the selector mechanism have been actuated. This means that the circuit of the switching device can only be closed after all the buttons of the selector mechanism have been actuated successively. If an order impulse is not received from the caller in correspondence with any particular button, or if one is received in correspondence with a button which was not pressed, the block-relay inserted in the switch circuit is actuated. This relay is so designed that once actuated it remains excited till the control process is terminated. This prevents the switch device, which may consist in a relay, being actuated by closing the cam-controlled contact inserted in the switch circuit. Only when the impulses arrive during the pauses following the pressing of the buttons forming the key is the action of the block-relay excluded. The switch circuit is closed after the cam-controlled contact has been actuated and the caller is connected with the electric apparatus or the process initiated.

A relay is provided for changing over from the transmitter that gives the signals to the receiver that registers the order impulses. This relay is actuated by means of a cam-controlled contact after each corresponding signal has been emitted.

In the foregoing the main circuits of the arrangement invented have been described. The details and the general construction of the whole circuit may be elucidated with the help of the accompanying drawing representing the diagram of the circuit of a specific embodiment of the arrangement according to the invention herein described.

The drawing represents the wiring of part 60 of a subscriber's station provided with a tele-

phonograph and connected with the telephone network by means of the cables 13, 14. If a call is made by any subscriber of this network destined for this subscriber's station, the connection between this subscriber, the exchange office, and the called subscriber's station is made by means known in themselves (not shown). The calling alternating current then sent out by the exchange office, goes through the cables 13, 14, the contacts 16, 17, and the condenser 15 to the relay R4, energizing the latter. This closes the contacts of this relay, which energizes the relay H6, provided with three windings, through its winding I. Of the three windings of this relay, the windings I and II serve for actuating the relay, while the winding III is bifilar incapable of setting the relay in operation. The relay H6 actuates the contacts 7, 8, 11, 16, 17 and 73 causing the following processes:

The relay MR18 is set in operation through the contact 8 and the winding I of the relay ST12, provided with three windings, causing this relay to become operative. The cables 13, 14 are disconnected from the relay R4 at the contacts 16, 17 and are connected with a circuit going through the contacts 29, 30 of the relay U49 and the outlet of the amplifier VAG31. At this point, the contacts 7 and 73 are still inoperative. The relay MR18, through its contact 19, closes the circuit of the motor M20 which is destined for driving the sound carrier TO33 and the cam disks NK1 to NK18 in forward or reverse movement. The relay ST12, which can be energized through each one of its three windings, is, after it has been energized in the said manner through its winding I, inserted in a holding circuit, which runs through a contact 66, closed by the cam of the cam disk NK14 in the position of rest of the latter, the operating contact 63 of the relay ST12 and the winding III of the relay ST12. Beside the contact 63, there have also been closed the contacts 56 and 61 of this relay, of which the former actuates the relay T57 and the latter the coupling magnet VK62; this magnet through a gear (not shown), couples the motor M20 with the cam disks NK1 to NK18 and the two coils S and T, on which has been wound the sound carrier TO33, for example, consisting of a steel wire, so that this sound carrier in the forward movement, and the cam disks are moved in the same sense in the direction shown in the drawing at the cam disk NK1.

The cam disk NK14, shortly after starting its movement, opens the contact 66, thereby opening the circuit passing through the winding III of the relay ST12 and disconnecting the relay. However, the cam disk NK15, immediately after starting, closed the contacts 59 and 60, keeping them closed continuously during one whole rotation. In this way, there are formed two holding circuits for the relay T57 and the coupling magnet VK62, which are independent of the relay ST12. The relay T51, when energized, incidentally keeps open the circuit of the coupling magnet RK45 for the reverse movement of the sound carrier TO33 and of the cam disks NK1 to NK18 at the contact 43 during the entire rotation of the cam disks. The recordings existing on the sound carrier TO33 which consist of a general message to the calling person and subsequently in a succession of numbers, for instance from 1 to 10, produce in the reproducing magnet SPK100 currents which are transmitted to the calling subscriber through the amplifier VAG31 and the cables 13, 14.

The circuit may now be explained with the help of a number of examples of correct, incorrect and repeatedly incorrect command, considering a selector mechanism with 10 buttons. Let the secret key be the number 146. This presupposes that of the keys T1 to T10, the keys T1, T4, and T6 have been confirmed by the owners of the telephonograph so that the contacts 84, 87, and 89 are closed. As will be seen from the subsequent description in detail, it is, for a correct control by the calling subscriber, now necessary for the latter, immediately after sounding those numbers of the series of numbers, emitted by the telephonograph, which correspond to the numbers of the secret number, thus, in the present case, after the numbers 1, 4, and 6, to speak into his microphone each time at least two impulses consisting of one sound each. On the other hand, when the remaining numbers of the series of numbers are sounded, in the present case after the numbers 2, 3, 5, 7, 8, 9, and 10, he must not give any sound impulses to his microphone.

1. Correct control

Immediately after the calling subscriber has heard the number 1, he will be switched from the amplifier VAG31, which serves for the amplification of the sounds coming from the reproducing magnet SPK100, to the amplifier VEG32 which serves for the amplification of the sounds coming from this subscriber. This is done by cam NK17 and relay U49 over the following circuit:

- (1) Earth, NK17, contact 101, relay U49, battery.

The calling subscriber is now connected with the amplifier VEG32 and can transmit any sound impulses to the called subscriber. The relay J28 is connected with the outlet of the amplifier and is energized by any such sound impulse thereby closing its operative contact 53. Simultaneously with switching on the relay U49 by the first cam of the cam disk NK17, the cam of the cam disk NK1 has also touched the lower contact spring of the contact 14, thereby closing this contact. By this action, the relay P98 is energized by the following circuit:

- (2) Earth, T1, contact 84, NK1, contact 14, relay P98, battery.

When the calling subscriber speaks the first of the two sound impulses to be sent out after the number 1, into his microphone, the relay L50 is actuated in the following circuit:

- (3) Earth, NK16, contact 58, contact 53, contact 51, relay L50, battery.

The relay C48 is provided with two windings I and II. However, it can be energized only through the winding I, since the winding II is bifilar. Before the relay L50 is energized, the winding I of the relay C48 is without current because of the open contacts 51, so that closing the contacts 53 of the relay J28 in regard to the relay C48 remains ineffective for the time being. If the relay L50 in the circuit 3 has been actuated and if the contact 53 is still closed, the relay C48 still cannot be energized, since on both ends of its winding I there is the same potential, that is through contacts 58, 53, and 47, on the one hand, and the contacts 102 and 51, on the other hand.

The relay L50, through its closed operating contacts 51, is now kept in the following circuit:

- (4) Earth, NK17, contact 102, contact 51, relay L50, battery.

The relay J28 is opened at the end of the first sound impulse transmitted from the calling subscriber, which causes the ground potential, which has been established through the contacts 58, 53, and 41 at the upper end of the winding I of the relay C48, to be disconnected. This relay is now actuated in the following circuit:

- (5) Earth, NK17, contact 102, contact 51, relay C48, winding I, bifilar winding II, battery.

The second order impulse given by the caller again attracts relay J28 and the following circuit is formed:

- (6) Earth, NK16, contact 58, contact 53, contact 47, contact 46, relay X24, winding I, battery.

It is obvious that the order impulses emitted by the caller or by the exchange will not always have the same length. In order to bring about that in all sound impulses the relay X24 remains energized until the relay P98 has been opened, the relay X24, which possesses three windings in all, of which each one can be used for its actuation after its energizing, is inserted in the following holding circuit:

- (7) Earth, condenser 22, contact 23, relay X24, winding II, battery.

The forward movement of the cams now interrupts circuits 1, 2, and 4. The opening of the relay U49 results in that the calling subscriber is switched from the amplifier VEG32 to the amplifier VAG31, whereupon he hears the number "2." The opening of the relay P98 results only in that another holding circuit is formed for the relay X24 in the following way:

- (8) Earth, NK16, contact 58, contact 54, contact 55, relay X24, winding III, battery.

The opening of the relay L50, because of the opened contact 102, causes also the opening of the relay C48 so that these two relays are again in the position of rest. In the meantime the cam of the cam disk NK2 has made contact in the lower contact spring of the contact 75. As, however, key T2 is not pressed, contact 85 is not closed, so that no circuit is formed and relay P98 cannot be excited. The calling subscriber has now received the number 2 and circuit 1 is again closed. As it was assumed that the order impulses are given correctly, no impulse is given after the number 2, so that relays L50 and C48 are not actuated.

The same process is repeated with the number 3, in connection with which likewise only circuit 1 is formed, as button T3 also remains unpressed and no impulse is received. On the contrary, the procedure in connection with number 4, i. e. after subscriber has received the number 4, resembles that following number 1, and the following circuit is formed:

- (9) Earth, T4, contact 87, NK4, contact 71, relay P98, battery.

Relay P98 is attracted and circuit 8 interrupted. Circuits 1 and 3 to 8 are reformed precisely as after the number 1.

After the number 5 conditions are identical with those prevailing after numbers 2 and 3, as button T5 is not pressed. Contact 88 remains open, so that even the closing of contact 78 by NK5 cannot excite relay P98. After the number 6 we have the same conditions as after number 4. Button T6 is pressed, closing contact 89, so that relay P98 is excited by the closing of contact 79 by cam NK6. The remaining buttons T7 to T10 with contacts 90, 91, 92, 93 and the corresponding cams NK7, 8, 9, 10 with contacts 80, 81, 82, 83, are not pressed, so that the situation is identical with that corresponding to buttons T2, 3 and 5. The correct control impulses have now been given and the following circuit is closed:

- (10) Earth, NK11, contact 95, contact 94, relay AN96, battery.

Upon putting the relay AN96 into operation, the contact 35 is closed by which any mechanical or electrical process may be released. This process may, for example, consist in connecting the main line 13, 14 of the telephonograph with a reproducing magnet likewise belonging to the latter, which magnet operates in conjunction with a steel band on which there are any desired recordings which the calling subscriber wishes to hear.

As soon as circuit 10 is closed contact 72 of the relay AN96 is interrupted. This prevents a second passage of the sound carrier TO33, as will be explained in detail below. The two cam disks NK12 and NK13 are arranged in such a way that, during the described rotation of the cam disks NK1—NK18, the contacts 67 and 68 are successively short-circuited once. While closing the contact 67, because of the opened operational contact 64 of the relay K69, remains without any effect, the contact 68 closes the following circuits:

- (11) Ground, contact 68, winding I of the relay K69, battery.

The relay K69 starts to operate and is kept in the circuit:

- (12) Ground, contact 73 of the relay H6, contact 72 of the relay AN96, contact 71 of the relay K69, winding II of this relay, battery.

As soon as the circuit 10 is closed in the above described manner, the circuit 12 is again interrupted, because the contact 72 of the relay AN96 is opened. As a result the relay K69 becomes inoperative. When the forward movement is completed power magnet VK62 and relay T51 are cut out by NK15. Making the magnet VK62 inoperative causes the sound carrier TO33 and the cam disks NK1—NK18 to stop. The inactivation of the relay T51 has the additional result that its resting contact 43 is closed, which forms the following circuit for the coupling magnet RK45 that produces the reverse movement of the sound carrier TO33 and of the cam disks NK1—NK18.

- (13) Earth, NK18, contact 41, contact 43, power magnet RK45, battery.

Accordingly, the sound carrier TO33 and the cam disks NK1—NK18 return to initial position, which causes in the latter the opening of the circuit of the magnet RK45 at contact 41 of the cam disk NK18. Since the relay K69 already 75 has been inactivated and since, in addition, in

the position of rest of the cam disks, the contact 42 of the cam disk NK18 is open also, the relay H6 cannot continue operating through its winding II and becomes inoperative. This opens all circuits which are still operating, and stops the telephonograph. In order to prevent any possibility for the subscriber to hear in reverse the message recorded on the sound carrier TO33 during the reverse movement of the latter, the reproducing magnet SPK100, during this reverse movement, is short-circuited by the contact 105 belonging to the relay T57 which remains inoperative during the reverse movement.

2. *Incorrect control and repetition of message*

Let it be assumed that the calling subscriber emits two impulses in connection with the number 2. The first impulse, as relay P98 was not excited, closes circuits 3, 4 and 5; whereas the second impulse closes the following circuit:

- (14) Earth, contact 58, contact 53, contact 47, contact 46, relay S27, winding I, battery.

The relay S27 is provided with three windings I, II, and III, of which each one can be used for actuating the relay. The relay, by its operating contact 52, is inserted in the following holding circuit:

- (15) Earth, NK16, contact 58, contact 52, 30 relay S27, winding III, battery.

The make and break contact 94 of relay S27 is inserted in the circuit of relay AN96 which it interrupts when excited. As soon as relay S27 is excited all other order impulses are rendered ineffective by this relay. If an impulse is received at a wrong moment, i. e. when the corresponding button has not been pressed, relay S27 is in any case excited and if, after the passage of all the button circuits, contact 95 of cam NK11 is actuated, a special circuit 36 is closed. This circuit can, for example, transmit a "busy" signal to the calling subscriber in the usual way. The following circuit is formed:

- (16) Earth, NK11, contact 95, contact 94, 45 relay AB97, battery.

Shortly before the cam NK15 has made a complete revolution, there is effected in the described manner the disconnection of the magnet VK62 for the forward movement, and the connection of the magnet RK45 for the reverse movement. The return movement takes place as already described. In contrast to the processes in correct control, after the termination of the reverse movement, the holding circuit 12 for the relay K69 has remained closed at the contact 72 of the relay AN96. As soon as cam NK16 has returned to its initial position the following circuit is formed:

- (17) Earth, NK18, contact 40, contact 38, contact 39, relay ST12, winding II, battery.

Holding the relay H6 is taken over by the circuit:

- (18) Earth, contact 106, contact 7, relay H6, winding II, and bifilar winding III, battery.

Connecting the relay ST12 produces another forward movement of the sound carrier TO33 of the cam disks NK1—NK18 which makes possible another emission of the sound impulses by the calling subscriber. At this second forward move-

ment relay Z65 which is provided with two windings I and II can be excited over circuit:

- (19) Earth, NK13, contact 67, contact 64, relay Z65, winding I, battery,

because at the first forward movement NK12 closed the circuit of winding I of relay 69 over contact 68. This relay is held over contact 71 and its winding II. At the first forward movement relay Z65 could not be actuated over contact 64, as NK13 closes contact 67 before NK12 closes contact 68.

Relay Z65 is held in the circuit:

- (20) Earth, contact 73, contact 72, contact 70, relay Z65, winding II, battery.

If the correct control impulses are given at the second forward movement, circuit 10 is closed, as described above. If other incorrect control impulses are given, the following circuit is formed after the completion of the return movement:

- (21) Earth, NK18, contact 99, contact 44, relay H6, bifilar winding III, battery.

This again cuts out relay H6 and all the relays return to their normal position.

So far the procedure occasioned by incorrect control impulses has been described. If, however, at a prearranged point, in the present case for example after the number 1, no impulse is emitted, circuits 3 to 7 are not excited. On the other hand, relay P98 is nevertheless attracted so that condenser 104 can be charged. On cutting out relay P98 the following circuit is formed:

- (22) Earth, condenser 104, contact 25, contact 26, relay S27, winding II, battery.

Relay S27 is now held by circuit 15. As already repeatedly mentioned, the attraction of relay S27 excludes the possibility of actuating relay AN96. It also closes the special circuit 36 with the help of relay AB97.

I claim:

1. In a control system for remotely actuating an apparatus, an electrical line, and a station comprising said apparatus, an impulse relay actuated by current impulses arriving over said line, a first intermediate relay connected with the contacts of said impulse relay and energized when said impulse relay is actuated by a current impulse, means for holding said first intermediate relay independently of said impulse relay after the first intermediate relay was actuated, a second intermediate relay connected with the contacts of the first intermediate relay to prepare its actuating circuit and also connected with the contacts of said impulse relay to be actuated on the end of the impulse operating said first intermediate relay, means for holding said second intermediate relay after its actuation independently of said impulse relay, electrical switching means, and an actuating circuit for said electrical switching means, said actuating circuit including contacts of said impulse relay and contacts of said second intermediate relay and actuating said electrical switching means upon receipt of at least two current impulses transmitted over said line.

2. In a control system for remotely actuating an apparatus, an electrical line and a station, in which said apparatus is located, a transmitter for transmitting signals over the line, means for causing the transmission of a number of signals by the transmitter at predetermined time intervals, a first set of switches to be manually actuated in accordance with a prearranged code, a

second set of switches including means for operating the switching of said second set one by one and each within one of said time intervals, a first relay, a set of circuits, each circuit being provided with a switch of each set of switches and adapted to operate said first relay when both switches are simultaneously in the operated position, a second relay adapted to be actuated by electrical impulses arriving over the line, a third relay, a circuit comprising contacts of said first and second relay and adapted to operate the third relay upon the arrival of electrical impulses not corresponding to said code, and circuit means for actuating the apparatus, the operation of the latter means being controlled by contacts of the third relay for preventing the apparatus from being actuated when the third relay has been operated.

3. In a control system for remotely actuating an apparatus, an electrical line and a station, in which said apparatus is located, a sound carrier having numerals of a numerological series recorded at intervals thereon, a device for reproducing said numerals electrically and for transmitting them over the line, a first set of switches to be manually actuated in accordance with a prearranged code, a second set of switches, a first relay, a set of circuits of which each is provided with a switch of each set of switches and is adapted to operate said first relay when both switches are simultaneously in the operated position, a second relay adapted to be actuated by electrical impulses arriving over the line, rotatable cam means adapted on the one hand to operate the switches of said second set of switches, each during the interval between the transmission of two numerals, and on the other hand to cause said second relay to be connected with the line during each of said intervals, driving means adapted to move the sound carrier and the cam means, a third relay, a circuit comprising contacts of said first and second relay and adapted to operate the third relay upon the arrival of electrical impulses not corresponding with said code, and circuit means for actuating the apparatus, the operation of the latter means being controlled by said cam means for actuating the apparatus after the transmission of said numerals and being further controlled by contacts of the said third relay to prevent the apparatus from being actuated when the third relay has been operated.

4. In a control system an electrical line and a station in which is located an apparatus to be actuated by electrical impulses transmitted over the line and corresponding to a predetermined code, electrical impulse receiving means responsive to impulses transmitted over the line, selective circuit elements set in accordance with said code, control means adapted for cyclic operation causing the selective circuit elements to become effective one after the other during each cycle, starting means connected with the control means for causing the latter to operate through one cycle, a relay and circuit connections between the contacts of the relay and the starting means for operating the latter by this relay, contact means controlled by said electrical impulse receiving means and said selective circuit elements, and a test circuit including said relay and said contact means for operating the relay upon the arrival of impulses not corresponding with the code and thereby causing the control means to operate through a further cycle.

5. In a control system, an electrical line and

75

a station, in which is located an apparatus to be actuated by electrical impulses transmitted over the line and corresponding to a predetermined code, electrical impulse receiving means responsive to impulses transmitted over the line, selective circuit elements set in accordance with the code, control means adapted for cyclic operation from an initial position and causing the selective circuit elements to become effective one after the other during each cycle, driving means for moving the control means out of said initial position and for automatically restoring them to this position, a test circuit comprising a relay and contact means, said contact means including contacts controlled by said electrical impulse receiving means and contacts controlled by said selective circuit elements for operating the relay upon the arrival during a first cycle of the control means of impulses not corresponding with the code, a starting circuit for said driving means including contacts of said relay and contacts associated with said control means and arranged to be operated thereby in their initial position, the starting circuit being provided to initiate the control means to operate through a further cycle when the impulses transmitted during said first cycle did not correspond with the code.

6. In a control system in combination with a transmitter, an electrical line and a station in which is located an apparatus to be actuated by electrical impulses transmitted over the line and corresponding to a predetermined code, electrical impulse receiving means including contacts to be operated by impulses transmitted over the line, circuit means including a relay and selective circuit elements set in accordance with the code, a time delay switch operating through a fixed range and adapted to govern said transmitter to transmit signals at predetermined time intervals over the line and to cause the circuit means to connect said selective circuit elements one by one and each during one of said time intervals with the said relay for operating it in accordance with the code, control means for causing the switch to move through said range, and a test circuit including the contacts controlled by the impulse receiving means, the contacts of said relay and the control means, which contacts are arranged to operate the control means and thereby to effect the repetition of a foregoing movement of the switch during which a series of impulses transmitted over the line did not correspond to the code.

MAX HANDSCHIN.
